CHENEY KILBURN AND ARTEMAS KILBURN, OF PHILADELPHIA, PENNSYLVANIA,
ASSIGNORS TO HALE, GOODMAN & CO., OF SAME PLACE.

Letters Patent No. 98,167, dated December 21, 1869.

IMPROVED MECHANISM FOR RAISING AND LOWERING BOARDS.

The Schedule referred to in these Letters Patent and making part of the same.

Be it known that we, CHENEY KILBURN and ARTEMAS KILBURN, (assignors to the firm of HALE, GOODMAN & CO.,) of Philadelphia, county of Philadelphia, and State of Pennsylvania, have invented certain Mechanism for Raising and Lowering Boards, &c., of which the following is a specification.

Nature and Object of the Invention.

Our invention relates to mechanism for raising and lowering boards, &c., in warehouses, sheds, and elsewhere; and

Our invention consists—

First, of two vertically-traversing chains, having certain projections, in combination with strips and boards, or their equivalents, the whole being so arranged and operating that the boards resting edgewise on the projections of the chains, may be thereby raised or lowered in, and guided by spaces afforded by the said strips;

Second, of certain safety driving-gear, described hereafter, in combination with the said endless chains;

Third, of certain inclined planes for directing the elevated boards on to the floor after leaving the machine;

Fourth, of certain curved projections for directing the elevated boards from the machine on to the said inclined planes;

Fifth, of certain arms which can be so adjusted as to direct the boards lowered by the machine on to the floor; and

Sixth, of certain arms which can be so adjusted as to present ledges whereon the boards can be placed edgewise, prior to being caught by the projections of the chains, and elevated.

Description of the Accompanying Drawing.

Figure 1 is an end elevation of our machine for raising, lowering, and delivering boards, &c.;

Figure 2, a front view of the same;

Figure 3, a vertical section on the line 1-2, fig. 2;

Figure 4, a top view;

Figure 5, a perspective view, illustrating the lower portion of the machine; and

Figure 6, a perspective view, illustrating the upper portion of the machine.

General Description.

The line A represents the ceiling or under side of the rafters of a room, of which B is the floor; and the line C represents the floor of the room or cellar below.

To the rafters A A are secured two hangers, D and D', carrying a shaft, E, on which is a worm-wheel, a, adapted to a worm on a driving-shaft, b, turning in hangers, F F, which are also secured to the rafters A, the shaft b being furnished with a suitable driving-pulley for receiving a belt.

Two chain-pulleys, G and G', are secured to the shaft E, an endless chain, H, passing round the former pulley, and a like chain, H', round the latter pulley, the chains also passing round similar pulleys on a shaft, I, which turns in standards J J, secured to the lower floor C.

Every other link of the two chains has a projection, e, or these projections may be otherwise so arranged on the chain, at such distances apart, that boards of ordinary width can be admitted between them. I prefer, however, to make the links so long that there may be a projection on every other link.

It is the duty of these endless chains to raise boards from the lower floor e to the floor B above, or to lower them from the upper floor to that below.

Each endless chain is partially enclosed by two boards or frames, K and K', which extend from the floor C upward through the floor B, and terminate a short distance above the same, and these boards are of such a width that the greater portion of the projections e of the links will extend beyond the edges of the said boards.

On one side of each endless chain is a vertical strip or shield, L, and there is a similar strip, L', on the opposite side, these strips being connected to the floor B, or secured in any other suitable manner, so that they shall occupy a position parallel with the chain and edges of the boards K and K', but so far from both that the boards to be hoisted can pass freely between them. (See fig. 1.) The inside of each strip has a vertical groove, into which the projections e of the links extend.

To each board K', near its upper end, is secured a strip or plate, f, on each end of which there is a curved projection, h, best observed on referring to fig. 1, and below these projections are the upper ends i i of the strips L and L'. Enlarged communications, m m, are thus left between the projections h h and tops of the strips to the vertical spaces between the said strips and the boards K and K'.

Inclined strips, n n, extend from the tops of the strips L and L' to the floor B, for a purpose described hereafter.

To each of the boards K, a short distance above the floor C, is hinged an arm, p, which can be elevated out of the way, as shown in fig. 5, or depressed to the floor, as shown (to the left) in fig. 1, thus presenting an inclined plane.

A similar arm is hinged to each of the boards K', so that the arm to the left may present an inclined plane while that to the right is elevated, as shown in fig. 1, or that to the left may be elevated while that to the right is depressed.

To each of the boards K' is hinged a small arm, q, which can be elevated out of the way, or depressed so

as to form a ledge on which to place the boards to be elevated. These arms are also arranged on the right and left in the same manner as the arms *p*.

It will be observed that the lower ends of the strips *L* and *L'* terminate a short distance above the point where the arms *p* and *q* are jointed to the boards *K* and *K'*.

Operation.

We will suppose the endless chain to be traversing in the direction of the arrows, fig. 1, and that it is desirable to elevate a number of boards on the lower floor *C*, and to deliver them on the floor *B* above.

The arms *p* on the right having been turned up, and the arms *q* depressed, the attendant places a board edgewise on the ledges afforded by the said arms *q*, and there leaves it, to fetch another board. In the mean time, the projections *e* on the chains catch the under side of the first board, elevate it, and introduce it into the space *x* between the edges of the boards *K* and *K'* and the strip *L'*. The first board having been elevated out of the way, another board is placed on the arms *q*, and this is also elevated by projections *e* on the chain. Thus board after board is caught and introduced into the space *x*, through which a succession of boards is constantly traversing upward.

When a board reaches the curved projection *m* above the floor *B*, its upper edge is turned outward, and it is finally thrown on to the inclined plane *n*, and thus delivered on to the floor *B*.

It may be necessary, however, to remove different boards from the floor *B* while the chains are still in motion. In this case, an attendant stationed to the left of the machine, fig. 1, introduces board after board edgewise into the enlarged space *m* between the top of the strip *L* and the projection *h*, and these boards resting on the descending projections *e* of the chains, are carried down with the latter, and finally delivered on to the inclined arms *p*, and on to the floor *C*. It will be thus seen that boards of one class may be elevated, and those of another class lowered at the same time.

The movement of the chains may at any time be reversed, and that side of the machine on which the elevating had been conducted may be used for lowering, all that is necessary, prior to this reversing, being a proper adjustment of the arms *p* and *q*.

We have described the machine as being arranged for removing boards from one floor to the next, but it will be understood that the machine may be arranged for conveying boards through a number of floors of a warehouse or shed, or the entire machine may be movable, and transferable from point to point of a lumber-yard, with the view of facilitating the erection or removal of piles of lumber.

Although we have alluded to *K* and *K'* as boards, it will be evident that light frames of metal may be used in their place.

For the purpose of driving the endless chain, we prefer the worm and worm-wheel described above, especially as the movement of the chains must be necessarily slow. This driving-gear, too, in addition to its simplicity, is self-locking, as regards any tendency which the chains might have to run down on the weighted side, should the driving-strap be broken, or escape from the pulley on the driving-shaft *B*.

Although we have described our invention as applied to the moving of lumber only, it will be found equally useful for raising and lowering plates of sheet-metal, long iron rods, &c.

Claims.

1. The vertically-traversing endless chains *H* and *H'*, with their projections *e* *e*, in combination with the strips *L* and *L'*, and boards *K*, or their equivalents.
2. In combination with the above, the shaft *E*, with its worm-wheel *a*, and the driving-shaft *b*, with its worm.
3. The inclined planes *n*, extending from the tops of the strips *L* and *L'* to the floor, as described.
4. The curved projections *h* *h* above the tops of the said strips.
5. The arms *p* *p*, arranged, in respect to the strips *L* and *L'*, and endless chains, as set forth.
6. The arms *q* *q*, arranged, in respect to the said strips and chains, as specified.

In testimony whereof, we have signed our names to this specification, in the presence of two subscribing witnesses.
